HAND-SUPPORTED LIQUID DISPENSING PAD

Carl C. Harris, Orange, Mass., assignor to Rivet-O
Manufacturing Co., Orange, Mass., a corpora-
tion of Massachusetts

Application April 9, 1943, Serial No. 482,459

11 Claims. (Cl. 91—54.4)

This invention relates to liquid-retaining and dispensing pads adapted to be worn upon the hand and the principal object of the invention is to provide a pad which may be easily applied to or removed from the back of the hand or wrist and having means by which it may be firmly retained in place without interfering with the free manipulation of the fingers in handling articles without transmitting liquid to the articles being handled.

I am aware that various moistening devices have been employed which are supported upon the palm of the hand or upon the end of a finger for use in moistening the fingers of the other hand for handling bank bills, papers, etc., or for moistening stamps and the like, but such devices are usually so constructed that in use the moistening liquid is likely to be inadvertently smeared upon the articles which are being handled.

One of the objects of the invention is to provide an inking or moistening pad so constructed and worn as to avoid such objectionable features.

Another object of the invention is to provide a liquid retaining and dispensing pad which may be readily detachably mounted upon the back of a first joint section of an intermediate finger of the hand and provided with means adapted firmly to be engaged by adjacent fingers in such manner as to permit free manipulation of the fingers.

Another object of the invention is to provide a liquid retaining and dispensing pad of the character described having legs adapted to rest upon a desk or other suitable support either more firmly to hold the pad in proper position while in use or to hold the pad upright when removed from the hand.

Another object of the invention is to provide an ink pad of the character described in which the ink dispensing surface of the pad is sufficiently below the level of the surrounding wall as to prevent engagement of the ink dispensing surface with the desk or other support even if the device is tilted or overturned.

Another object of the invention is to provide a moistening pad of the character described in which the liquid dispensing surface projects above the surrounding wall to enable the adhesive surfaces of stamps, envelope flaps, etc. to be readily applied to and moved across it or which can be more conveniently touched by the fingers of the other hand when used in manipulating bank notes or other papers.

Another object of the invention is to provide an inking pad of the character described with means for releasably holding an inking stamp

above and in proximity to the surface of the inking pad thereby avoiding the inconvenience of laying down and picking up the stamp between its times of use and also providing an assemblage which will avoid the mislaying of the stamp or pad when not in use.

These and other objects and features of the invention will more fully appear from the following description and the accompanying drawing and will be particularly pointed out in the claims.

Preferred embodiments of the invention are illustrated in the accompanying drawing, in which,

Fig. 1 is a perspective view of the liquid retaining and dispensing device in the form of an inking pad when mounted upon the hand of the operator;

Fig. 2 is a side elevation of the same illustrating means for supporting the pad and showing in dotted lines the positions of the fingers of the hand and a support upon which the ends of the supporting legs may rest;

Fig. 3 is a central transverse sectional view of the inking pad shown in Figs. 1 and 2;

Fig. 4 is a perspective view illustrating the manner in which the inking device may be applied to the inside of a finger upon the hand and retained thereon by adjacent fingers;

Fig. 5 is a transverse sectional view of a moistening pad embodying the invention;

Fig. 6 is a plan view of the inking pad showing the means for supporting an inking stamp, the neck of the inking stamp being shown in horizontal section;

Fig. 7 is a side elevation of the inking pad, the inking stamp, and the means for supporting the same in proximity to the ink dispensing surface of the pad; and

Fig. 8 illustrates a modified form of the invention as applied to the wrist.

The inking pad illustrated comprises a suitable receptacle or casing 1, which, as illustrated, is of cylindrical form but may be of any desired shape or size, having a chamber 2 in which is mounted a suitable liquid retaining and dispensing pad 3. The pad preferably is of sponge rubber but may be of any suitable character which provides a liquid distributing or dispensing surface. In the inking pad construction illustrated the upper edge 4 of the peripheral wall of the receptacle extends well above the surface of the liquid retaining and dispensing member and protects the surface from inadvertent contact with the desk or materials thereon, even if the device is tilted or upset.

The means for supporting the inking pad pref-

erably comprises a flat rigid strap 5 of suitable material which is secured to the base 6 of the receptacle in any suitable manner as by a rivet or stud 7 which extends through the center of the pad through a washer 8 and is provided with an upset end 9 serving firmly to secure the parts together and prevent leakage of the liquid.

The strap 5 is formed of oppositely extending legs 10 and 11 which curve downwardly, then outwardly and desirably upwardly at their ends to provide flat feet 12 and 13 adapted to rest upon a suitable base 14 to support the device in upright position when not in use. The strap 5 desirably is made of flat stiff but pliable material so that the legs thereof can be bent to conform to the fingers of the particular operator who uses it.

Preferably the pad is mounted upon the first joint section of the second or longest finger 15 and the leg 11 extends downwardly between the finger 15 and the finger 16 and beneath the latter. The leg 10 similarly extends downwardly between the second finger 15 and the third finger 17 and beneath the latter, as illustrated in Fig. 2. By then depressing the first and third fingers relatively to the second finger the pad is firmly held in upright position upon the back of the second finger. By thus supporting the pad upon the first joint of the second finger free manipulation of all the fingers is permitted.

Of course the pad may also be supported upon the plantar joint of the third finger if desired.

The invention when embodied in a moistening pad is of substantially the same construction except that the liquid retaining and moistening member or pad 18 desirably extends above the edge of the surrounding wall 4 so that the full dispensing surface of the pad can be presented when used to moisten stamps, envelope flaps, or other devices having an adhesive surface or can be more readily touched by the fingers of the other hand in manipulating bills, papers, etc., it being noted that where a moistening pad is used in this manner the fingers of the hand upon which the liquid retaining and dispensing device is mounted can be freely manipulated to hold the bills, papers, or any other articles without interference with the use of the moistening device.

It sometimes is convenient to have the moistening device on the inside of the hand instead of on the back and the construction is such that by a mere reversal of the device the casing may be supported upon the inside of the first joint section of the second or other intermediate finger with the legs extending over the backs of the adjacent fingers, as shown in Fig. 4, in which case the thumb of the hand can be readily pressed upon the liquid dispensing surface.

It will be apparent that by reason of the present construction the inking pad will be held firmly by engagement of the legs of the strap with an intermediate finger and the next adjacent fingers, but it will also be noted that the ends of the legs 10 and 11 are in the form of flat feet 12 and 13 which may be placed upon a desk or other suitable flat support more rigidly to hold the device in upright position and also to relieve the strain upon the fingers which otherwise would be required to hold the device in proper position.

A further object of the invention is to provide an inking pad with means for detachably supporting the inking stamp in such manner that it can be easily removed and used and replaced, thereby avoiding the necessity of laying the stamp down with the attendant possibility of smearing

papers and which will also insure the stamp and pad being together when they are to be used.

A preferred construction which is illustrated in Figs. 6 and 7 comprises a wire clamping device 5 having legs 19 and 20 which are mounted in suitable bores or sockets in the base 6 of the pad and have sections extending vertically upwardly therefrom and then preferably provided with curved portions 21 and 22 which extend horizontally over the inking pad and are connected by an integral open loop 23 adapted resiliently to embrace the handle 24 of an inking stamp 25 of a usual character, the loop member 23 desirably being located at such distance from the dispensing face of the pad that the face of the stamp will be held in close proximity to or if desirable in contact with said ink dispensing surface.

By reason of the diametrical position of the strap 5 relatively to the receptacle the device 20 may be applied to the hand with the open portion of the loop of the stamp supporting member toward the end of the fingers or toward the back of the hand as may be most convenient to the operator.

The loop portion desirably is in axial alignment with the receptacle so that when the device is placed upon a desk it will remain upright notwithstanding the weight of the stamp.

A modified form of the invention is illustrated in Fig. 8 in which the strap 5 is so formed that the legs 10 and 11 thereof embrace the wrist of the operator and differs therefrom in that the ends desirably are curved into circular form to provide feet 26 and 27 adapted to rest upon the suitable base 14. The receptacle 4 employed in this construction may be of any desirable shape or size and may be equipped with an inking pad having its ink dispensing surface below the plane of the upper edge of the wall of the receptacle, as illustrated in Fig. 3, or if used for a moistening device the dispensing surface of the liquid retaining device may extend well above the upper edge of the wall, as heretofore described.

By reason of the present construction a liquid retaining and dispensing device is provided which can be easily carried upon the hand and will be of convenient access at all times notwithstanding the movement of the operator from one place to another.

50 When used as an inking pad by an operator who, for example, is checking time cards, the hand is sufficiently free to enable him to shuffle or rearrange the cards and the ink pad is always handy for use, whereas in many instances there would be no convenient place for him to put the inking pad.

The receptacle and pad may be made of any suitable light materials and its construction is such that when held firmly by the hand it will not have a tendency to revolve or otherwise change its position when pressure is applied to it by the stamp.

When not in use it will be properly supported upon its legs and in any event will not tip over in such manner as to cause the ink distributing surface to contact with and smear other articles.

It will be understood that the particular embodiment of the invention shown and described herein is of an illustrative character and is not restrictive and that various changes in form, construction and arrangement of parts may be made within the spirit and scope of the following claims.

Having thus described the invention, what is

claimed as new, and desired to be secured by Letters Patent, is

1. A liquid retaining and dispensing device adapted to be worn upon the hand comprising a rigid receptacle, containing a liquid absorbent material and presenting a liquid dispensing surface, having a base adapted to be mounted upon an intermediate finger of the hand, rigid retaining members extending oppositely therefrom between and partially around and effectively engaging fingers respectively adjacent to said intermediate finger.

2. A liquid retaining and dispensing device adapted to be worn upon the hand comprising a rigid receptacle, containing a liquid absorbent material and presenting a liquid dispensing surface, having a base adapted to be mounted upon an intermediate finger of the hand and rigid flat retaining members of bendable material connected to said receptacle extending in opposite directions therefrom between said intermediate finger and the respective fingers next adjacent thereto and effectively engaging the next adjacent fingers.

3. An inking pad adapted to be worn upon the hand comprising a rigid receptacle containing an ink absorbent material and presenting an ink dispensing surface, having a base having a flat strap secured thereto adapted to rest upon the back of the first joint member of an intermediate finger of the hand provided with reversely bent legs extending downwardly from diametrically opposite sides of said receptacle between said intermediate finger and the respective adjacent fingers and thence outwardly beneath said respective adjacent fingers.

4. An inking pad adapted to be worn upon the hand comprising a rigid receptacle containing an ink absorbent material and presenting an ink dispensing surface, having a base having a flat strap secured thereto, adapted to rest upon the back of the first joint member of the second finger, provided with reversely bent legs extending downwardly from diametrically opposite sides of said receptacle between the second finger and the respective adjacent fingers and beyond the adjacent fingers sufficiently to be engaged and further supported by the thumb and little finger.

5. An inking pad adapted to be worn upon the hand comprising a rigid receptacle, containing an ink absorbent material presenting a liquid dispensing surface and having a base having a flat strap secured thereto, adapted to rest upon and be supported by the back of the hand, provided with reversely curved flat legs extending downwardly from diametrically opposite portions thereto substantially equal distances and thence outwardly to form feet adapted to support said receptacle when in use and which will also support it in upright position when removed from the hand.

6. An inking pad comprising a rigid receptacle containing an ink absorbent material presenting a substantially flat liquid dispensing surface, means for supporting said receptacle upon the hand and resilient means mounted on said receptacle having means to engage the stamp and hold the face thereof in proximity to said ink dispensing surface.

7. An inking pad comprising a rigid receptacle containing an ink absorbent material presenting a substantially flat liquid dispensing surface, means for supporting said receptacle upon the

hand and a resilient wire having its ends mounted in the walls of said receptacle provided with an intermediate open loop overlying and spaced from the liquid dispensing surface of said pad adapted detachably to engage the handle portion of a stamp and hold the face of the stamp in proximity to said ink dispensing surface.

8. An inking pad adapted to be worn upon the hand comprising a rigid receptacle, an ink retaining and dispensing pad mounted therein with the ink dispensing surface well below the plane of the upper edge of the receptacle, a flat strap secured to the base and extending diametrically in opposite directions therefrom having downwardly extending curved legs to embrace a member of the hand or the wrist and position said receptacle upon the back thereof and provided with reversely bent feet having a sufficiently wide surface to retain the device in upright position when resting upon a flat support.

9. A moistening pad adapted to be worn upon the hand comprising a rigid receptacle, a liquid retaining and dispensing pad mounted therein with the liquid dispensing surface well above the plane of the upper edge of the receptacle, a flat strap secured to the base and extending diametrically therefrom having downwardly extending curved legs to embrace a member of the hand or the wrist and to retain the liquid dispensing device upon the back thereof and provided with cylindrically curved feet adapted to rest upon a supporting surface in such manner as to aid in holding the device rigid in upright position when in use and also to retain the device in upright position when removed from the hand.

10. A material retaining and dispensing device adapted to be worn upon the hand, comprising a receptacle forming a reservoir for the material and containing a pad of porous material presenting a substantially flat dispensing surface, a flat retaining member secured to said receptacle adapted to be mounted centrally upon an intermediate finger and extending in diametrically opposite directions and having reversely bent legs adapted respectively to extend between the intermediate finger of the hand and the fingers next adjacent thereto and to engage opposite sides of said adjacent fingers thereby to enable said adjacent fingers to clamp the device firmly upon said intermediate finger in upright relation thereto.

11. A material retaining and dispensing device adapted to be worn upon the hand, comprising a receptacle forming a reservoir for the material and containing a pad of porous material presenting a substantially flat dispensing surface, a flat retaining member secured to said receptacle adapted to be mounted centrally upon an intermediate finger and extending in diametrically opposite directions and having reversely bent legs adapted respectively to extend between the intermediate finger of the hand and the fingers next adjacent thereto and to engage opposite sides of said adjacent fingers thereby to enable said adjacent fingers to clamp the device firmly upon said intermediate finger in upright relation thereto, the ends of said legs having foot portions to engage a suitable support to aid in holding the device in upright position during use and also to retain the device in upright position when removed from the hand.

CARL C. HARRIS.
